United States Patent Office

Des. 184,438
Patented Feb. 17, 1959

184,438

VELOCIPED

Carl W. Hedstrom, Gardner, Mass., assignor to Hedstrom
Union Company, Fitchburg, Mass.

Application May 26, 1958, Serial No. 51,089

Term of patent 7 years

(Cl. D34—15)

Fig. 1.

Fig. 2.

Fig. 3.

Fig. 1 is a side elevation of a velocipede embodying my new design;

Fig. 2 is a rear elevation thereof; and

Fig. 3 is a fragmentary perspective view of the rear portion thereof with the rear axle and rear wheels omitted for ease of illustration.

The essential features of the present design are shown by solid lines.

I claim:

The ornamental design for a velocipede, as shown and described.
